UNITED STATES PATENT OFFICE.

HENRY BREHMER, OF NEW YORK, N. Y., ASSIGNOR TO DAVID WOLFE BRUCE,
OF SAME PLACE.

DESIGN FOR A FONT OF TYPE.

SPECIFICATION forming part of Design No. 18,560, dated August 28, 1888.

Application filed July 12, 1888. Serial No. 279,895. Term of patent 14 years.

To all whom it may concern:

Be it known that I, HENRY BREHMER, a citizen of the United States, residing at New York, in the county of New York and State of New York, (assignor to DAVID WOLFE BRUCE,) have invented a new and original Design for a Font of Printing-Types, of which the following is a specification.

The nature of my design is fully and clearly shown in the accompanying typographic impressions, to which reference is made, in which are comprised capital and lower-case letters, punctuation-marks, numerals, and the dollar and pound (sterling) symbols, many of which have a grotesque text resemblance, whose main characteristic points are medium light weight of all the stem-lines, the curve-lines tapering up to equal weight at their heaviest portions, the omission of the horizontal right lines commonly used for ceriphs and cross-lines and the substitution therefor and for many of the curve-lines of tendril-like lines having dot or leaf-like termination, and varying in each letter in weight, number, position, curve, and direction of curve, as well as in termination, according to the character of the letter. Of these tendril-like lines, the first is the short curved line starting from the upper end of the stem-line of the capital letter B a short distance below the point formed by the junction of the two and curving toward the left and upward to its dot termination; also shown in similar position in the capital letters D, E, K, and R. The second is the complement of the first, having its weight increased to harmonize with that of the stem-line and the angular junction forming a short point similar to that of the first. This is shown attached to the lower end of the stem-line in the capital letters B, D, E, K, L, and R. The third is simply the second having additional length to its curve and terminating in a short diagonal spur-line, which supports the shortened stem-line which also terminates in the heavy portion of its curve. The third is shown supporting the stem-lines of the capital letters F, I, P, T, and Y. It is also shown supporting the left-hand limbs of the capital letters A, M, N, and X, also forming the connection at the lower ends of the first and second limbs of the capital letters V and W. The fourth is the curve-line with dot termination forming the cross-bar to the capital letters A and H, the tongue of the capital letter E, and the upper portion of the

beard of the capital letter G. It is also found terminating the upper and lower curve-lines of the capital letter B, and in similar use in the capital letters P, R, and U and the numerals 4, 6, 7, and 9, and in the cipher. The fifth is the curve-line forming the tongue of the capital letter E and having the leaf-like termination. It is shown best in the upper and lower terminations of the curve-lines of the numeral 3, and free or in combination with other lines in the capital letters C, E, F, G, J, L, O, Q, S, and Z, the &, the numerals 2, 5, 6, 8, and 9, and the dollar and pound symbols. The sixth is a short hair-line with dot termination similar to a musical quarter-note shown attached to the right-hand sides of the upper and lower curve-lines of the capital letter E. They are also shown in the capital letters C, F, G, L, S, and Z, the lower-case letters s and z, and with a slight curve in the lower-case letter r and the numerals 2 and 7.

The lower-case letters all are without the horizontal ceriphs; but the diagonal lines and angles used in the ordinary text letter are used where practicable and convenient. This is best seen in the lower-case letter l, which, as will be observed, has the diagonal line at the top and the slight angle with diagonal line attached at the bottom.

Minor characteristics are the slight angle produced in the right-hand curve-line of the lower-case letters h m n and the slight inward curve below that angle, the combination of two or more of the tendril-like lines, as shown in the capital letters C, D, J, L, O, P, Q, R, and U, lower-case letters c and r, and the dollarsymbol.

The punctuation-marks are conventional, as allowing but slight modification; but the exclamation and interrogation marks are in character with the capital letters and numerals.

What I claim as my invention, and desire to secure by Letters Patent, is

The design for a font of printing-types in which is comprised capital and lower-case letters, punctuation-marks, numerals, and the dollar and pound symbols, formed by a combination of the medium light weight in stem and taper of curve-lines, tendril-like lines, the diagonal lines, and angles, all substantially as shown and described.

HENRY BREHMER.
